(57) **CLAIM**

The ornamental design for a wedge shaped container configuration with packaging material, as shown and described.

DESCRIPTION

FIG. 1 is a top perspective view of a first embodiment of a wedge shaped container configuration with packaging material showing our new design;

FIG. 2 is a top view thereof;

FIG. 3 is a front view thereof;

FIG. 4 is a right side view thereof with the left side view being identical;

FIG. 5 is a back view thereof;

FIG. 6 is a bottom view thereof;

FIG. 7 is a top perspective view of a second embodiment of a wedge shaped container configuration with packaging material showing our new design;

FIG. 8 is a top view thereof;

FIG. 9 is a front view thereof;

FIG. 10 is a right side view thereof with the left side view being identical;

FIG. 11 is a back view thereof; and,

FIG. 12 is a bottom view thereof.

The broken line showing of FIGS. 1–12 is included for the purpose of illustrating container tab portions and packaging material and forms no part of the claimed design.
